COMB

John C. Norris, Strong, Ark.

Application December 17, 1954, Serial No. 475,903

4 Claims. (Cl. 132—158)

The present invention relates to a barber's comb having specially formed teeth permitting close application of clippers and shears.

The primary object of the present invention is to provide an improved barber's comb having specially formed teeth at one end by means of which the hair may be feathered easily with shears or clippers.

Another object of the present invention is to provide a new and improved barber's comb having specially formed teeth at the small end of the comb which readily separate and pick up the hair and are separated from each other by other specially formed teeth which reinforce and strengthen that end of the comb.

A further object of the present invention is to provide a barber's comb permitting the use of a clipper close to the scalp without leaving the usual clipper marks.

These and other objects and advantages of the present invention will be fully apparent from the following description when taken in connection with the annexed drawings, in which:

Figure 1 is a side view in elevation of the present invention,

Figure 2 is an end view of the present invention on line 2—2 of Figure 1,

Figure 3 is an end view in cross-section on line 3—3 of Figure 1,

Figure 4 is an end view in cross-section on line 4—4 of Figure 1, and

Figure 5 is a further end view in cross-section on line 5—5 of Figure 1.

Referring in greater detail to the drawings in which like numerals indicate like parts throughout the several views, the present invention consists of a comb body 10 having a plurality of teeth disposed in parallel spaced relation with respect to each other and lying in the same plane of and in substantial alignment with the comb back 11, the teeth increasing in length from the one end 12 of the comb body 10 to the other end 13.

The comb is roughly divided in half at a median line and the teeth 14 which are disposed between the median line and the end 13 of the comb are the longer teeth and form a first comb section. Referring to Figure 3, one of the teeth 14 is seen to be attached to the comb back 11 and has a forward or front face 15 tapering from a point adjacent its attachment with the comb back 11 to its free end, the front face 15 and the back face 16 of each of the teeth 14 are flat and taper from the comb back 11.

Disposed between the median line and the one end 12 of the comb body 10 is a second comb section having two types of teeth, 18 and 19, the first of which is seen in end profile in Figure 4, and is seen to have a back face 20 which is flat for a portion of its area and a front face 21 which tapers from a point adjacent its attachment to the comb back 11 to its free end 22 where it forms a point with the curved end portion 23 of the back face 20. Each of the teeth 18 is also tapered on its side edges from a point intermediate of its ends to its free end, as best seen in front elevational view of Figure 1.

2

Each of the teeth 19 is disposed intermediately between adjacent teeth 18 and has parallel side faces and a back face 24 which is flat for a portion of its area and terminates in an end portion 25 which is curved to meet the end of the front face 26 in a point, the front face also tapering from a point adjacent its attachment to the comb back 11 to its free end.

The teeth 18 and 19 alternate one with the other for the full length of the second comb section.

The teeth 18 are stronger and serve to reinforce the structure of the comb so that the barber is less likely to bend them to the point of breaking.

The curved end portions 23 and 25 of the teeth 18 and 19, respectively, permit the barber to apply the shears or clipper to the head of the person getting a haircut without scratching the person's head.

The curved end portions of the teeth 14 permit the comb to be used on relatively heavy hair and permit the comb to enter the hair easily.

While only a preferred embodiment of the present invention is shown and described, other embodiments may be made and practiced within the scope of the appended claims without departing from the spirit of the invention.

What is claimed is:

25 1. A comb comprising a body having a comb back and a plurality of teeth disposed in parallel spaced relation, each of said teeth lying in the same plane of and in substantial alignment with said comb back and being attached by one end to said comb back, the teeth disposed between

30 a median line of said body and one end thereof forming a first comb section, each of the teeth of said first comb section having a back face which is flat for a portion of its area and being tapered in thickness from a point adjacent its attachment to said comb back to its free end, the

35 remainder of the teeth on said body forming a second comb section, certain ones of the teeth of said second comb section each having a back face which is flat for a portion of its area and being tapered in thickness from a point adjacent its attachment to said comb back to its free end,

40 the back face of each of the latter named teeth terminating in a curved portion forming a point with the end of the front face of the respective one of the latter named teeth, the free ends of all of the teeth of the first and second comb sections ending in a common plane.

45 2. A comb comprising a body having a comb back and a plurality of teeth disposed in parallel spaced relation, each of said teeth lying in the same plane of and in substantial alignment with said comb back and being attached by one end to said comb back, the teeth disposed between

50 a median line of said body and one end thereof forming a first comb section, each of the teeth of said first comb section having a back face which is flat for a portion of its area and being tapered in thickness from a point adjacent its attachment to said comb back to its free end,

55 the remainder of the teeth on said body forming a second comb section, alternate ones of the teeth of said second comb section each having a back face which is flat for a portion of its area and being tapered in thickness from a point adjacent its attachment to said comb back to its free end, the back face of each of the latter named teeth terminating in a curved portion forming a point with the end of the front face of the respective one of the latter named teeth, the free ends of all of the teeth of the first and second comb sections ending in a common plane.

60 3. A comb comprising a body having a comb back and a plurality of teeth disposed in parallel spaced relation, each of said teeth lying in the same plane of and in substantial alignment with said comb back and being attached by one end to said comb back, the teeth disposed between

65 a median line of said body and one end thereof forming a first comb section, each of the teeth of said first comb section having a back face which is flat for a portion of its area and being tapered in thickness from a point adjacent its attachment to said comb back to its free end,

70 the back face of each of the latter named teeth terminating in a curved portion forming a point with the end of the front face of the respective one of the latter named teeth, the free ends of all of the teeth of the first and second comb sections ending in a common plane.

its area and being tapered in thickness from a point adjacent its attachment to said comb back to its free end, the remainder of the teeth on said body forming a second comb section, alternate ones of the teeth of said second comb section each having a back face which is flat for a portion of its area and being tapered in thickness from a point adjacent its attachment to said comb back to its free end, the back face of each of the latter named teeth terminating in a curved portion forming a point with the end of the front face of the respective one of the latter named teeth, the free ends of all of the teeth of the first and second comb sections ending in a common plane, each of said alternate teeth of said second comb section having its side face tapering from a point intermediate of its ends to its free end.

4. A comb comprising a body having a comb back and a plurality of teeth disposed in parallel spaced relation, each of said teeth lying in the same plane of and in substantial alignment with said comb back and being attached by one end to said comb back, the teeth disposed between a median line of said body and one end thereof forming a first comb section, each of the teeth of said first comb section having a back face which is flat for a portion of its area and being tapered in thickness from a point adjacent its attachment to said comb back to its free end, the remainder of the teeth on said body forming a second

5 comb section, alternate ones of the teeth of said second comb section each having a back face which is flat for a portion of its area and being tapered in thickness from a point adjacent its attachment to said comb back to its free end, the back face of each of the latter named teeth terminating in a curved portion forming a point with the end of the front face of the respective one of the latter named teeth, the free ends of all of the teeth of the first and second comb sections ending in a common plane, 10 each of said alternate teeth of said second comb section having its side face tapering from a point intermediate of its ends to its free end, each of the teeth of said second comb section disposed intermediate of said alternate teeth having parallel side faces.
